PARTITIONED CONTAINER

Jules M. Reaves, Memphis, Tenn., assignor of fifty
per cent to Heiskell Weatherford, Jr., Memphis,
Tenn.

Application June 21, 1948, Serial No. 34,229

4 Claims. (Cl. 229—27)

1

This invention relates to new and useful improvements in containers, and particularly relates to a container which is adapted for use as a mold and which may be readily formed in a new and novel manner from a single blank.

The invention further relates to container blanks which may be readily and economically manufactured without waste of material.

The present invention has largely resulted from a need found in the packaging of substances such as oleomargarine and butter and is primarily adapted for utilization in connection with such products. It, however, as will readily be seen from the following specification, is not limited to such uses, but may be readily adapted for many other uses.

The principal object of the invention is to provide a blank from which a container may be readily formed in a new and novel manner by the folding and fastening of the parts thereof.

A further object of the invention is to provide a container which includes novel means adapted to receive and retain partitions or dividers.

A further object of the invention is to provide a container blank which may readily be formed from a sheet of flexible material without waste of material from such sheet.

And a further object of the invention is to generally improve the design, utility and efficiency of containers.

The means by which the foregoing and other objects of this invention are accomplished and the manner of their accomplishment will readily be understood from the following specification upon reference to the accompanying drawings, in which:

Fig. 1 is a plan view of a preferred embodiment of the container blank of the present invention, showing in relation thereto a portion of an adjoining blank which has been formed from the sheet material.

Fig. 2 is a perspective view of a container formed from the blank illustrated in Fig. 1, showing the partitions thereof in position.

Fig. 3 is a top plan view of the formed container of Fig. 2.

Fig. 4 is a fragmentary sectional plan view on an enlarged scale, taken on the line IV—IV of Fig. 2, with the partitions removed.

Fig. 5 is a view similar to Fig. 1 of a variation in the embodiment of the container blank.

Fig. 6 is a perspective view, similar to Fig. 2, of a container formed from the blank of Fig. 5.

Fig. 7 is a top plan view of the container shown in Fig. 6; and

2

Fig. 8 is a fragmentary sectional plan view on an enlarged scale, similar to Fig. 4, taken on the line VIII—VIII of Fig. 6.

Referring now to the drawings in which the various parts are indicated by numerals:

The blanks for the containers of the present invention are formed from a sheet, preferably of flexible material, as for example, waxed cardboard or the like. The blanks include a base portion 11, side walls 13 and 15, and end walls 17, 19. The body portion is shown as square, although it may be rectangular if desired. The side walls 13 and 15 are respectively integrally attached and hinged along one edge to opposite edges of the base 11 along fold lines 21, 23 and the end walls are similarly attached and hinged along one edge to the remaining opposite edges of base 11 along fold lines 25, 27.

It will be seen that the side walls 13, 15 include integral longitudinally disposed extensions 29, 31, the extension 29 being hinged to one end of the side wall 13 along the fold line 33 and extending thereto. It will be noted that fold line 33 comprises a continuation of fold line 25, and that the attachment of extension 29 to side wall 13 is adjacent end wall 17. The extension 31 is similarly hinged to the end of wall 15 adjacent end wall 19 along fold line 35, which similarly comprises an extension of fold line 27 and extension 31 extends thereto in a direction opposite to that of extension 29. The end wall 17 preferably is slotted throughout its depth by spaced slots 37, being thereby divided into tabs 17A, and similarly the wall 19 is preferably divided by slots 39 into tabs 19A. At their remote ends extensions 29, 31 are respectively provided with integral terminal portions 41, 43, which are respectively hinged to the extensions along fold lines 45, 47.

In the preferred form of blank, as illustrated in Fig. 1, extensions 29, 31 are respectively of a length equal to the length of end walls 17, 19.

In the variation of the container blank as shown in Fig. 5, there is included a base 111, similar to the base 11, to opposite edges of which side walls 113, 115 are integrally and hingedly attached along fold lines 121, 123 and end walls 117, 119 are similarly integrally and hingedly attached to the remaining opposite edges of base 111 along fold lines 125, 127. The end walls 117, 119 are preferably divided by slots 137, 139 into a plurality of tabs 17A and 19A.

Hingedly attached to one end of side wall 113, as along the fold line 133, is an integral extension 129 which extends longitudinally beyond the hinged attachment. Oppositely extending from

the opposite end of side wall 113 is an integral extension 130 which is hingedly attached to the said opposite end, as along the fold line 134. It will be seen that the fold line 133 comprises a continuation of the fold line 125 and that the fold line 134 comprises a similar extension of the opposite fold line 127.

It will be noted that the extension 130 is preferably of a greater length than the length of extension 129 and exceeds in its length the width of a plurality of tabs 119A formed in end wall 119, the present illustration being shown as of a length substantially equal to two and one-half times the width of one of the tabs 119A.

Side wall 115 is similarly provided with extensions 131, 132, extension 131 being hingedly attached to one end of side wall 115 along the fold line 135 which comprises an extension of fold line 127 and the extension 132 being hingedly attached to the opposite end of side wall 115 along fold line 136 which comprises a continuation of fold line 125 extending therefrom oppositely to fold line 129.

It will be noted that while the foregoing description has referred to the container blanks as being made of flexible material of the nature of cardboard or the like, the container blanks may as readily be formed of sheet metal or other suitable material if desired.

In the formation of containers from the blanks of this invention, the side walls 13, 15 and end walls 17, 19 are folded upwardly along their respective fold lines 21, 23, 25, 27 to vertical position relative to the base 11. When the walls are thus positioned the slots 37, 39 of the end walls will be seen to be vertically disposed, and the extensions 29, 31 and their respective terminals 41, 43 will be seen to be vertically disposed and respectively projecting longitudinally beyond the adjacent end walls. The extensions 29, 31 are then folded inwardly along their respective fold lines 33, 35 until they are brought into contact with and lie along the outer surface of the respective end walls 17, 19. The extensions 29, 31 may be attached to the respective end walls by suitable adhesive or other attaching means, not shown.

When thus positioned the terminal portion 41 will be seen to project beyond the side wall 15 which is opposite to the side wall 13 to which the terminal portion 41 is connected by extension 29. Similarly, the terminal portion 43 is projected beyond the side wall 13 opposite to the side wall 15 to which the terminal portion 43 is connected by the extension 31. The respective terminal portions 41, 43 are then folded inwardly along their respective fold lines 45, 47 so that they are brought into contact with and lie along a portion of the outer surface of the respectively opposite side walls, in which position they may be attached by the use of adhesive or other suitable means.

It will thus be seen that a box-like container is formed, which, in its preferred form, is maintained in its folded container position through the fastening means comprising the respective extensions and terminal portions. It will also be seen that as the respective extensions 29, 31 lie along and in intimate contact with the outer surface of the end walls 17 and 19, the vertically disposed slots 37, 39 are thereby converted into vertically disposed sockets which are adapted to receive and retain the opposite end portions of vertically disposed partitions 49.

It will be noted that the extensions of the side walls substantially completely cover the

outer surface of the end walls and provide a backing therefor, converting the end walls into walls of double thickness, providing additional strength and rigidity therefor and greatly improving the quality of the containers thus formed.

In similar manner the container is formed from the blank as illustrated in Figs. 5 to 8 by the upward folding of the walls 113, 115, 117, 119 to position them in vertical position relative to the base 111 and the respective extensions 129, 130, 131, 132 are inwardly folded along their fold lines until they are brought into contact with and lie along the outer surface of the respective end walls 117, 119. The side wall extension portions are similarly attached to the outer surfaces of the end walls by suitable adhesive or other attaching means, and it will be seen that the vertically disposed slots 137, 139 are outwardly covered and thereby converted into sockets adapted to receive partitions 149 which are substantially identical with the partitions 49 hereinabove mentioned.

It will be seen that in manner similar to the manner already described for the containers formed from the blank illustrated in Figs. 1 to 4, the outer surfaces of the end walls of the containers formed from the blank of Fig. 5, as shown in Fig. 6 and 7, are substantially completely covered by the side wall extensions and are retained in position and braced thereby in manner similar to that already described.

In both Fig. 1 and Fig. 5, the conservation of material in the formation of the container blanks of this invention is readily apparent. As illustrated in each of those figures, the partitions 49 and 149 are severed from the sheet material in the same operation in which the individual blanks are severed and the arrangement of the parts is such that all of the material of the sheet is utilized in the formation of the blanks and of the partitions.

It is found that it is particularly useful to provide, as in the present invention, for the ready insertion and removal of the partitions, enabling the greater flexibility of space arrangement within the container. The container is, in addition, particularly well adapted for use as a mold for substances such as butter or oleomargarine which may be packed in bulk in the container without division or partition. When the bulk is removed for processing the partitions may be introduced into the respective sockets, effectively dividing the interior of the container, as illustrated, and the product, such as the butter or oleomargarine, may then be reintroduced after processing into the container, the partitions serving to divide, and upon hardening, to mold the substance into parcels or sticks of desirable size or shape.

When material such as metal is employed in the container structure it is found extremely useful in the sorting and handling of small objects, such as nails, screws, and in many instances fishing tackle, such as plugs, hooks and the like.

It will be understood that the foregoing description has described two of the preferred embodiments of the present invention, but, except insofar as hereinafter limited in the appended claims, modification in the precise form or arrangement of the parts may be had without departing from the scope hereof.

I claim:

1. A container comprising a horizontal quadrilateral base, a pair of opposite side walls re-

spectively attached to opposite edges of said base, and a pair of end walls respectively attached to the remaining edges of said base, said walls being folded upwardly from said base and vertically disposed in edge relation thereto, said end walls each including a plurality of vertical slots, each slot extending through its end wall from top to bottom thereof, an extension attached at one end to an end of one of said side walls extending therefrom and lying along the outer surface of one of said end walls in covering contact with said outer surface, a second extension attached at one end to the other said side wall extending therefrom and lying along the outer surface of the other said end wall in covering contact with the latter said outer surface, said covering contacts effecting outward closure of said slots, said slots remaining open at their tops and inwardly of said container, and a plurality of partitions, positioned with opposite end portions retained in said outwardly closed slots, said end portions being vertically slidable in said closed slots.

2. A container comprising a square base, a pair of opposite side walls respectively attached to opposite edges of said base, and a pair of end walls respectively attached to the remaining edges of said base, said walls being folded upwardly from said base and vertically disposed in edge relation thereto, said end walls each including a plurality of vertical slots, each slot extending through its end wall from top to bottom thereof, an extension of length greater than the width of an end wall attached at one end to an end of one of said side walls extending therefrom and lying along the outer surface of one of said end walls in covering contact with said outer surface, a second extension of length similar to that of the first said extension attached at one end to the other said side wall extending therefrom and lying along the outer surface of the other said end wall in covering contact with the latter said outer surface, said covering contacts effecting closure of said slots, said extensions each having a terminal portion attached to its other end, the terminal portion of the first said extension lying along and in contact with a portion of the outer surface of the said other side wall, and the terminal portion of the second extension lying along and in contact with the outer surface of the first said side wall, said terminal portions being respectively fastened to the opposite side wall contacted.

3. A container comprising a quadrilateral base, a pair of opposite side walls respectively attached to opposite edges of said base, and a pair of end walls respectively attached to the remaining edges of said base, said walls being folded upwardly from said base and vertically disposed in edge relation thereto, an extension integrally

attached at one end to an end of one of said side walls extending therefrom and lying along the outer surface of one of said end walls in covering contact with said outer surface, a second extension integrally attached at one end to the other said side wall extending therefrom and lying along the outer surface of the other said end wall in covering contact with the latter said outer surface, said extensions each having a terminal portion attached to its other end, the terminal portion of the first said extension lying along and in contact with a portion of the outer surface of the said other side wall, and the terminal portion of the second extension lying along and in contact with the outer surface of the first said side wall, said terminal portions being respectively fastened to the side walls contacted.

4. A container comprising a square base, a pair of opposite side walls respectively attached to opposite edges of said base, and a pair of end walls respectively attached to the remaining edges of said base, said walls being folded upwardly from said base and vertically disposed in edge relation thereto, said end walls each including a plurality of vertical slots, each slot extending through its end wall from top to bottom thereof, an extension attached at one end to an end of one of said side walls extending therefrom and lying along the outer surface of one of said end walls in covering contact with said outer surface, a second extension attached at one end to the other said side wall extending therefrom and lying along the outer surface of the other said end wall in covering contact with the latter said outer surface, said covering contacts effecting closure of said slots, said extensions each having a terminal portion attached to its other end, the terminal portion of the first said extension lying along and in contact with a portion of the outer surface of the said other side wall, and the terminal portion of the second extension lying along and in contact with the outer surface of the first said side wall, said terminal portions being respectively fastened to the side wall contacted, and partition means having opposite end portions slidably engaging, said closed slots.
